CONTAINER SEALING DEVICE

Carl C. Grotnes, Park Ridge, Ill., assignor of one-half to George G. Cuttner, Chicago, Ill.

Application February 2, 1940, Serial No. 316,912

4 Claims. (Cl. 24—68)

The invention relates to container sealing devices of the split ring type for clamping in place the cover of a container such as a metal drum, pail, barrel, or the like.

Containers of the character indicated are commonly provided with a peripheral bead at one end and over this is fitted a complementary marginal flange of a removable cover or end member. To clamp the cover in place a split ring of channel shaped cross section is clamped about it, various means having been provided for drawing the ring tight.

Generally stated, it is an object of the present invention to provide a sealing device of the type set forth embodying an improved and simplified mechanism for tightening or loosening the clamping ring, which is of such character as not only to be very simple to manipulate, but also very low in cost. This minimization of cost is accomplished in large part through a reduction in the number and size of the parts required, as well as by a simplification of their assembly and the elimination of as many pivotal joints and the like as possible.

Another object is to provide such a device embodying means for effectually pressing the ends of the split ring laterally inward into firm engagement with the underlying cover and container parts when in clamped position so that the cover is effectually sealed about its entire periphery.

Still another object is to provide such a device which combines good leverage ratios in a lever system for manipulating the clamping ring even though the levers are of minimum size, this action being accompanied by distortion of the ring in applying it to the container and in removing it.

Further objects and advantages of the invention will become apparent as the following description proceeds, taken in connection with the accompanying drawings in which:

Figure 1 is a fragmentary general perspective view of a paint pail provided with a sealing device embodying the invention.

Fig. 2 is a fragmentary plan view of the sealing device in its closed position.

Fig. 3 is a plan view of the sealing device in its open position.

Fig. 4 is an enlarged fragmentary perspective view of the sealing device in its open position.

Fig. 5 is an enlarged transverse sectional view along the line 5—5 in Fig. 2.

Fig. 6 is an enlarged transverse sectional view along the line 6—6 in Fig. 1.

Fig. 7 is a fragmentary perspective view of a metal barrel provided with a modified form of sealing device embodying the invention.

Fig. 8 is a plan view of the modified form of sealing device.

Figs. 9 and 10 are front elevations of the sealing device of Fig. 7 in its closed and open positions respectively.

Fig. 11 is an enlarged fragmentary perspective view of the sealing device of Fig. 7.

Fig. 12 is an enlarged transverse sectional view taken along the line 12—12 in Fig. 9.

Referring more particularly to Fig. 1, the invention has been illustrated as embodied in a sealing device for clamping in place the cover 10 of a metal paint pail 11 of well known form. This cover has a marginal flange or bead 12 which fits over a complementary bead (not shown) on the lip of the pail. To hold the cover securely in position it is embraced by a split clamping ring 13, drawn tight about it by a mechanism described below.

The split ring 13 is made of flexible, and preferably resilient metal, such as a fairly light gauge sheet steel. It is channel shaped in cross section, half round in the present instance (see Fig. 4). Its top edge overlies the cover bead 12 while its lower edges project inward beneath the shoulder on the bottom side of the bead formed on the end of the pail. Split rings constructed for such engagement with a cover and pail bead are well known in the art and, consequently, need not be further detailed here.

The improved and simplified mechanism for manipulating the clamping ring 13 to draw it tight, or to release it, comprises a laterally flexible metal strap 14 (see Fig. 4) which is arranged to span the gap between the ends of the split ring 13. One end of this strap 14 is spot welded or otherwise fixed to the crown of an end portion of the split ring as, for example, at 15. The cost and inconvenience of a pivotal connection between the strap and ring at this point are eliminated by utilizing the flexibility of the strap to

accomplish the necessary movement between it and the ring. The free end of the strap 14 is connected, as hereinafter described, to an operating lever 16 pivoted on the other end portion of the clamping ring. This operating lever is also of half round channel shaped cross section and is curved longitudinally (see Fig. 2) so as to conform with the curvature of the ring 13 and fit snugly along the periphery of the latter when the lever is in its retracted position.

In order to form a simple, but rugged pivotal

support for the lever 16 a channel shaped metal pivot block 17 (Figs. 4 and 5) is spot welded on the end portion of the ring in embracing relation with it. Rigid with, and projecting from the sides of, the block 17 are pivot pins 18 which are received in complementary holes in the arms 19 of a yoke shaped inner end of the lever 16. This yoke or bifurcated end is provided on the lever 16 so that the lever can be swung into fully retracted position (Fig. 2) without interference from the pivot block 17. It will be observed that the lever is thus pivoted to swing about an axis paralleling the axis of the ring 13 or, in other words, to move substantially in the plane of the ring.

To form a pivotal connection between the free end of the strap 14 and an intermediate portion of the lever 16 a hole 20 is provided in the latter (Figs. 4 and 6). In this hole is received an integral hook shaped projection 21 on the end of the strap. A hole 22 is formed in the ring 13 in a position to register in the hole 20 when the lever is retracted so that the hook 21 is received in the hole 22 (Fig. 6) and, hence, any obstruction to full retraction of the lever eliminated. Consequently, when the lever 16 is retracted it fits snugly along the periphery of the ring 13 so that the lever and strap 14 do not form an unsightly projection or bulge on the container nor do they interfere with stacking and packing of the containers.

In applying the sealing device described to the container 11, the lever 16 is swung outward substantially to the position of Fig. 3. Consequently, the strap 14 is flexed laterally outwardly and at the same time forced endwise toward the end of the ring 13 to which it is fixed so that the ends of the split ring are spread apart as shown. The expanded ring is then positioned to encircle the end of the cover (Fig. 1) and the lever 16 retracted to the position of Fig. 2. By this retraction of the lever the strap 14 is drawn inward toward the ring and at the same time is drawn endwise toward the lever so that the ends of the split ring are pulled together substantially into abutting engagement and the ring tightly clamps the container cover in place. To hold the lever 16 in this retracted position a removable U-shaped snap spring 23 (Figs. 2 and 3) is arranged to overlie the end of the lever with its ends engaged in notches 24 in the ring 13. To open the container it is only necessary to remove the snap spring 23 and swing the lever 16 outward to the position of Fig. 3, whereupon the ring 13 is expanded and disengaged from the container.

In drawing the ends of the split ring together in the manner described above there is some tendency to pull them laterally away from the container which is, of course, undesirable since there should be a tight seal about the entire periphery of the cover 10. To overcome this difficulty a longitudinal ridge is fashioned on the inner face of the strap 14, this ridge being formed in the present instance, by an indentation 25 (Figs. 4 and 5). This ridge presses firmly against the end portions of the ring 13 and forces them inward when the lever 16 is retracted so that the ring 13 effectually seals the entire perimeter of the cover.

In Figs. 7 to 12 a modified form of sealing device has been illustrated which also embodies the invention. In this instance the device is designed primarily for clamping a cover 10^a on a drum or barrel 11^a. Although the general form

of the container is the same as for the paint pail 11, described above, the larger size of the container 11^a necessitates a heavier and more powerful sealing device. As before, a split clamping ring 13^a is used which is of channel shaped, half round cross section and embraces the overlapping cover flange 11^a and container bead (see Fig. 13). The usual rubber gasket 12^b is arranged between the crown of the cover bead and the underlying portion of the barrel rim bead.

Also, as in the case of the device of Figs. 1 to 6, a metal strap spans the gap between the ends of the split ring and one end is rigidly fixed to an end portion of the ring. In this instance, however, a strap 14^a of quarter round cross section is used so that the end portions of the ring can be shifted relative to each other in a direction transverse to the plane of the ring without interference by the strap (see Fig. 11). The strap 14^a is riveted or otherwise rigidly secured at one end to an end portion of the ring 13^a and is disposed so as to overlie only one side face of the ring. Similarly, the operating lever 16^a is of quarter round cross section and also overlies only the same side face of the ring as that on which the strap is located.

The lever 16^a is pivoted by a pin 18^a on the ring 13^a to swing about an axis lying in the plane of the ring or, in other words, so that the lever swings transversely to the plane of the ring rather than in the plane of the ring, as in the previous case. Furthermore, the strap 14^a is laterally rigid and necessary displacement of the ring ends for movement of the lever is accommodated by twisting of the ring (compare Figs. 9 and 10). The lever conforms to the contour of the exterior of the ring 13^a so that when in its retracted position (Fig. 9) it fits snugly over the same.

Particularly to be noted is the form of pivotal connection between the free end of the strap 14^a and an intermediate portion of the lever 16^a. For this purpose a pin and slot or lost motion pivotal connection is utilized, comprising a pin 20^a fixed on the lever and received in a transverse slot 21^a in the end portion of the strap. The slot 21^a is fashioned so that when the pin 20^a is at its lower end and the lever 16^a retracted (Fig. 9) the end portions of the ring 13^a will lie in a common plane. On the other hand, when the lever 16^a is swung to its ring-expanding position (Fig. 10) the pin 20^a can rise to the upper end of the slot 21^a. In this way the skewing or twisting of the ring 13^a incident to opening of the ring is minimized. To put it another way, the angle α (Fig. 10) between the center lines of the respective ends of the split ring is minimized, even though quite a short strap 14^a is used. By this means maximum effectualness of operation is combined with parts of minimum length, and, hence, of minimum weight and cost.

In the operation of this modified form of the device the ring 13^a is first expanded for application to the container. To this end the lever 16^a is swung away from the ring (to the position of Fig. 10). In the course of such lever movement the strap 14^a is thrust endwise in a direction away from the lever, thereby forcing apart the ends of the ring 13^a and expanding it. As previously noted, the pin 20^a rises to the upper end of the slot 21^a so that twisting of the ring is minimized even though the now angularly disposed strap is rigid with one end of the ring. The cut away end portions of the strap and lever (Fig.

11) adjacent their respective pivoted ends permit complete freedom of movement for them.

Having expanded the ring 13^a as described, it is positioned to encircle the end of the container, and the lever 16^a is retracted to draw the ring tight. For this purpose the lever is swung from the position of Fig. 10 to that of Fig. 9. During this lever movement the pin 20^a rides down to the lower or bottom end of the slot 21^a and then the pull of the lever is transmitted through it to the strap 14^a to draw the latter endwise. As the strap is drawn endwise the ring 13^a is contracted until, at the end of the lever movement, the ring ends are in substantially abutting engagement. With the linkage 14^a, 16^a in the retracted position of Fig. 9 the strap and lever telescope or fit snugly about the ring so as to minimize protrusion from it and to reinforce the ring at its split.

Means is provided to seal the lever 16^a against movement from its retracted position and thus prevent tampering with the closed container. To this end an integral lug or bracket 30^a is formed on the free end of the lever and projects over the barrel head. On the lug 30^a is pivoted an eccentric locking member 31^a. This stamped sheet metal member 31^a presents an edge flange 32^a facing the inner side of the cover flange 12^a (Fig. 12). The curvature of this flange is eccentric to the pivot for the member 31^a. Accordingly, when the member 31^a is swung toward the flange 12^a (to the position of Fig. 12) it is tightly pressed against the cover flange, holding the lever 16^a against displacement. The outer wall of the lever 16^a is extended down as indicated at 16^b (Fig. 7) to form a reenforcing wall opposite the locking member 31^a. Registering holes 33^a are formed in the free end of the member 31^a, and in a lug 34^a on the lever 16^a, to receive a sealing wire 35^a for preventing release of the locking member 31^a without leaving signs of tampering.

I claim as my invention:

1. A sealing device of the type set forth, comprising, in combination, a split ring, a laterally flexible metal strap spanning the gap between the ring ends and fixed rigidly at one end to an end portion of the ring, means on the other end of said ring for drawing said strap endwise toward said other end of the ring and also laterally inward toward the ring, and a longitudinal ridge on the inner face of said strap to press the ring ends inwardly when the strap is drawn laterally in against the same.

2. In a sealing device of the character indi-

cated, the combination of a split ring, a laterally flexible metal strap spanning the gap between the ring ends and fixed rigidly at one end to an end portion of the ring, a lever pivoted on the other end portion of the ring to swing about an axis parallel to the ring axis, said lever having a hole therein intermediate its ends, and an integral hook shaped projection on the free end of said strap engaged in said hole to pivotally connect the strap and lever, said lever being curved longitudinally to conform to the curvature of the portion of the ring which it overlies when retracted.

3. A sealing device of the type set forth comprising, in combination, a split ring of channel shaped cross section, a laterally flexible metal strap arranged to span the gap between the ring ends and fixed rigidly at one end to the crown of the ring adjacent one end of the latter, a lever pivotally connected to the other end of the split ring, said lever also being of channel shaped cross section and curved longitudinally to conform to the curvature of the ring so as to fit snugly about the exterior of the latter when swung into engagement with it, said lever having a hole therein intermediate its ends, said strap having a hook shaped projection on its free end engaged in said hole to form a pivotal connection between the strap and lever, and said ring having a recess therein registering with said hole in the lever to receive the nose of said projection when the lever is swung toward the ring.

4. In a sealing device of the character set forth, the combination of a split clamping ring of channel shaped half round cross section, a laterally flexible metal strap rigidly fixed at one end to one end portion of the ring and disposed with the free end of the strap projecting toward the other end portion of the ring, an operating lever of half round cross section and curved in a longitudinal direction to conform with the curvature of the ring to thereby fit snugly along the exterior of the latter, a channel shaped member fixed to said other end portion of the ring and having laterally projecting pivot pins thereon, said lever having a yoke shaped end arranged with the arms of the yoke pivoted on said pins for pivotal movement of the lever about an axis paralleling the axis of the ring, and means forming a flexible connection between the free end of the strap and an intermediate portion of said lever.

CARL C. GROTNES.
